UNITED STATES PATENT OFFICE.

JOSEPH P. MARKS, OF PHILADELPHIA, PENNSYLVANIA, ASSIGNOR, BY DIRECT AND MESNE ASSIGNMENTS, OF TWO-THIRDS TO JOHN L. LARSEN AND CHARLES H. DAY, OF PHILADELPHIA, PENNSYLVANIA.

INKING-ROLL FOR PRINTING-PRESSES.

SPECIFICATION forming part of Letters Patent No. 699,110, dated April 29, 1902.

Application filed August 3, 1901. Serial No. 70,744. (No model.)

To all whom it may concern:

Be it known that I, JOSEPH P. MARKS, a citizen of the United States, residing in the city and county of Philadelphia, State of Pennsylvania, have invented a new and useful Improvement in Inking-Rolls for Printing-Presses, of which the following is a specification.

My invention consists of an improved inking-roll for printing-presses, as will be hereinafter fully described and claimed.

Figure 1 represents a side elevation of a portion of a frame of a printing-press provided with a truck embodying my invention. Fig. 2 represents a section thereof, taken on line *x x*, Fig. 3, with certain parts shown in dotted lines for convenience of illustration. Fig. 3 represents a section taken on line *y y*, Fig. 1. Fig. 4 represents a side elevation of a portion 20 of the frame and an inking-roll, showing the parts in another position. Fig. 5 represents a section thereof.

Similar letters of reference indicate corresponding parts in the figures.

Referring to the drawings, A designates a portion of the frame of the printing-press, and B the inking-roll. Said inking-roll is mounted upon a tube C, that is free to rotate upon a shaft D, the ends of which are held 30 by the yoke ends of the carriage E. Rigidly secured to the shaft D at the ends of the tube C are eccentrics F, and mounted to rotate freely upon these eccentrics are the trucks G. Said trucks G are held in place by means of 35 a flange H at the inner end of the eccentric, that fits within the annular groove in the adjacent part of the truck, while the other end of the truck is retained by means of a nut J, that screws upon the reduced end portion K 40 of said eccentric.

The end of the shaft D situated within the yoke E of the carriage is provided with a stop or shoulder L, which limits the rotation of the shaft relative to said carriage.

M designates the inking-disk of the press.

The operation is as follows: The object of the invention is to raise the inking-roll from

the type as the roller descends and to move it into contact with the type as the roll ascends, and upon reference to Figs. 1 and 2 50 it will be noticed that a truck G is in contact with the frame, while the ink-roll B is raised. The parts are brought to this position owing to the fact that when the truck rolls upon the upper end of the frame there is sufficient friction between it and the eccentric carried by the shaft to turn said parts in the same direction as that in which the truck is rolling until the stop or shoulder L strikes the said yoke, as shown in Fig. 1. This throws the 60 eccentric to the position shown in Fig. 2, which raises the ink-roll sufficiently to prevent it from coming in contact with the type. The parts remain in this position during the downward movement of the ink-rolls and carriage, the truck G rolling upon the frame and rotating freely upon the eccentric F. When the roller reaches its lower limit and then begins to ascend, the trucks rotate in the opposite direction and turn the eccentric G and 65 shaft D in the opposite direction until the stop or shoulder L strikes the other side of the yoke, as in Fig. 4. This brings the eccentric to the position best shown in Fig. 5 and moves the ink-roll into contact with the 70 type, the face-line of the type being indicated in dotted lines in Figs. 4 and 5, as will be evident. The parts remain in this position throughout the entire upward movement and until the carriage again moves downward. 75 80

Having thus described my invention, what I claim as new, and desire to secure by Letters Patent, is—

1. In a printing-press, a carriage, an inking-roll shaft carried thereby and having a limited rotary movement relative thereto, an ink-roll rotatably mounted upon the said shaft, eccentrics rigid with said shaft, and trucks rotatably mounted upon said eccentrics. 85

2. In a printing-press, a carriage having a yoke, an ink-roll shaft rotatably mounted in said yoke and having stops or shoulders to limit the rotary movement thereof, an ink-roll rotatably mounted upon said shaft, ec- 90

centrics mounted upon said shaft at the ends of said roll, and trucks rotatably mounted upon said eccentrics.

3. In a printing-press, a carriage having 5 yokes, an ink-roll shaft rotatably mounted in said yokes and provided with stops to limit the rotation thereof, an ink-roll rotatably mounted upon the said shaft, eccentrics rig-

idly secured to said shaft at the ends of said ink-roll, and trucks rotatably mounted upon said eccentrics.

JOSEPH P. MARKS.
